David Hathaway - Design for a Sewer Plate
Assigned to Messrs. Fuller, Warren & Morrison, Troy, N.Y.

Des 976

Patented Jan'y 12. 1858.

Dec. 976

David Hathaway, of Troy N.Y.

Assignor to -

Fuller Warren & Morrison of same place.

Letters Patent No. 976. Dated Jan. 12th 1858.

The schedule referred to in these Letters Patent and making part of the same.

To all whom it may concern: -

Be it known that I, David Hathaway, of the city of Troy, in the County of Rensselaer, and State of New York, have invented or produced a new and original Design for the Front or back Plate of a Cottage Parlor Stove; and I do hereby declare that the following is a full and exact description of the same reference being had to the annexed photographic drawing making a part of this specification.

My ornamental design for the front or back plate of a cottage parlor stove consists, of the row of drops, a, pendant from the cornice, b; the pairs of high central and low side, semi-cylindrical pilasters, c, c', united together at top by the half round semi-circular arches d, standing upon the part b, - and guarding the door-like panels e, - each of which latter is ornamented by the supported shell f; - the interrupted molding g; the curved panels h; and the projecting top pieces i; having end pendants j; - the several parts being shaped and arranged upon the plate in the

Des. 976

particular manner shown in and by the annexed photograph. -

What I claim as my invention or production and desire to secure by Letters Patent is, the ornamental design herein described and fully represented in the annexed photographic drawing, for a stove plate.
